UNITED STATES PATENT OFFICE.

THOMAS C. IGO, OF CLEVELAND, OHIO.

DESIGN FOR A LENS FOR AN AUTOMOBILE LAMP.

Application filed May 24, 1921. Serial No. 472,266. Term of patent 3½ years.

To all whom it may concern:

Be it known that I, THOMAS C. Igo, a citizen of the United States, residing at Cleveland, in the county of Cuyahoga and State of Ohio, have invented a new, original, and ornamental Design for Lenses for Automobile Lamps, of which the following is a specification, reference being had to the accompanying drawing, forming part thereof.

Figure 1 is a face view of a lens for an automobile lamp, showing my new design, and

Fig. 2 is a central transverse sectional view of the same.

The shaded portion in Fig. 1 of the drawings represents a different color from the remainder of the lens.

I claim:

The ornamental design for a lens for an automobile lamp, as shown.

In testimony whereof I affix my signature.

THOMAS C. IGO.
